UNITED STATES PATENT OFFICE.

HENRY C. McBURNEY, OF LOS ANGELES, CALIFORNIA.

MAY-POLE.

1,177,426.

Specification of Letters Patent. Patented Mar. 28, 1916.

Application filed July 15, 1915. Serial No. 40,072.

To all whom it may concern:

Be it known that I, HENRY C. McBURNEY, a citizen of the United States, residing at Los Angeles, in the county of Los Angeles and State of California, have invented certain new and useful Improvements in May-Poles; and I do hereby declare the following to be a full, clear, and exact description of the invention, such as will enable others skilled in the art to which it appertains to make and use the same.

The general object of this invention is to improve the construction of May poles, by increasing the stability of the pole and rendering the pole more attractive, and by admitting of the pole being conveniently handled so as to be placed at various points and to be manufactured cheaply; and to this end the invention consists in the provision of a frusto-conical base, sufficiently weighted so as to maintain an upright position, a vertically disposed pole member mounted in the base, a circular plate rotatably mounted on the upper end of the pole and adapted to support drapery, means associated with the pole to be moved into engagement with the plate, so as to hold the latter against rotation.

Other objects will appear and will be better understood from that embodiment of my invention of which the following is a specification, reference being had to the accompanying drawing forming a part thereof, in which—

Figure 1 is a vertical elevation of the May pole and showing the base for the pole in section, Fig. 2 is a detail sectional view taken through the upper end of the pole and the plate, and Fig. 3 is a top plan view of the circular plate used in connection with the May pole.

Referring to the drawing in detail, the numeral 1 designates the frusto-conical shaped base having a filling therein consisting of an upper and lower layer of concrete designated respectively by the numerals 2 and 3, and an intermediate layer of wood shavings or excelsior 4. This particular filling renders the base more stable and yet admits the same being rendered light enough to be conveniently lifted. Embedded within the layers 2, 3 and 4 and concentrically located is a vertically disposed stud 5. The lower end of the stud 5 lies flush with the lower surface of the lower layer 3, and the upper end extends into the central opening

6 which has its upper end opening into the upper end of the base and its lower end located adjacent the lower side of the upper layer 2, the walls of the opening being spaced from the upper end of the stud, as shown in Fig. 1. Projecting through the opening 6 is the lower end of a vertically disposed tubular upright 7, the said lower end of the tubular upright receiving the upper end of the stud, as shown in Fig. 1, and the upper end of the tubular member being disposed a considerable distance above the upper end of the base 1.

The vertically disposed upright 6 receives the lower end of a vertical pole 8, the said lower end of the pole terminally resting upon the upper end of the stud. The upper end of the pole 8 has mounted thereupon a circular plate 9. This plate 9 is provided with a concentrically disposed opening 10 which registers with the longitudinal opening 11 in the upper end of the pole 8 for the accommodation of a flag staff 12 which serves as means for holding the plate in position on the pole, and also to provide a bearing for the plate. The periphery of the plate 8 is provided with a plurality of staples 13 arranged in spaced relation about the periphery of the plate, and the respective staples are adapted to receive the rings 14. The rings 14 are adapted to have secured thereto the upper ends of vertically disposed strips of drapery or strands of ribbon or the like, said strips or strands being of different colors to give an attractive appearance to the structure, the lower ends of the strips or strands extending downwardly a sufficient distance to be grasped by persons positioned around the pole.

The pole 8 has associated therewith a locking element adapted to be moved into engagement with the plate and hold the latter against rotation. The locking element consists of a sliding bolt 16 located within a tubular casing 17, the said sliding bolt 16 being adapted when moved upwardly to have its upper end received by one of the pair of openings 18 formed in the under side of the plate 9. The means for moving the sliding bolt 16 upwardly consists of a rod 19, which as shown in Fig. 2 has one end secured, within an eye 20 in the lower end of the sliding bolt 16, the lower end of the rod being provided with a manipulating handle 21 which is adapted for sliding

movement within a recess formed in the casing 22 and to be moved laterally into slcts 23 and 24, so as to hold the sliding bolt in either locking or unlocking position.

5 In use, the strips or strands 15 are held by different persons and the persons holding the strands march around the pole. If the locking bolt 16 is in unlocking position, the plate 9 can have free rotation resulting in a very attractive display of the strands or strips. If it is desirous to wind the strands around the pole so as to give a highly attractive and extraordinary appearance to the pole, the bolt 16 is moved into engagement with one of the openings 18 and the persons holding the strips or strands march around the pole in alternate directions, resulting in the spiral winding of the strands around the pole and the alternate display of the colors.

Having thus described my invention, what I claim as new is:

1. A device of the character described comprising a hollow base, a filling within the base, and including upper and lower layers of heavy material, and an intermediate layer of lighter material, a vertically disposed stud embedded within the material, a vertically disposed tubular member having

its lower end extending into the base and receiving the upper end of the stud, a pole extending into the upper end of the vertically disposed tubular member.

2. A May pole comprising, a base, a pole carried by the base, a vertically sliding bolt mounted on the pole, a circular plate rotatably mounted on the pole and provided with a plurality of openings adapted to alternately align with the bolt during rotation of the plate, means associated with the bolt for sliding the bolt upwardly to engage the same in one of the openings in the circular plate so as to hold the plate against rotation, a manipulating member carried by the bolt for sliding the bolt downwardly and from engagement with the openings, so as to permit the plate to rotate, and means carried by the pole for engaging the manipulating member when in the last mentioned position, so as to hold the bolt against upward travel.

In testimony whereof I affix my signature in presence of two witnesses.

HENRY C. McBURNEY.
